UNITED STATES PATENT OFFICE.

PHILIP MORGAN, OF LINDSAY, ONTARIO, CANADA.

PHONOGRAPH-RECORD HOLDER.

1,409,392.

Specification of Letters Patent. Patented Mar. 14, 1922.

Application filed June 10, 1920. Serial No. 387,996.

To all whom it may concern:

Be it known that I, PHILIP MORGAN, a subject of the King of Great Britain, and resident of the town of Lindsay, county of 5 Victoria, Province of Ontario, in the Dominion of Canada, have invented certain new and useful Improvements in Phonograph-Record Holders, described in the following specification and illustrated in the 10 accompanying drawings, that form part of the same.

The principal objects of this invention are, to facilitate the handling of phonograph records and to provide a form of holder 15 which will keep the records in good condition and enable their being handled with ease and without danger of marring same.

A still further object is to devise a holder which will have an extraordinary storage 20 capacity for records.

The principal feature of the invention consists in the arrangement of a plurality of arms upon a pivotal support, said arms being adapted to carry the records and to be 25 swung upon the support independently the one of the other.

In the drawings, Figure 1 is a perspective view of my improved record holder.

Figure 2 is an enlarged vertical elevational 30 sectional view through a portion of the device.

The device consists of a bracket arm 1 which is here shown of tubular form and may be of any desirable shape to be attached 35 to a cabinet or stand either rigidly or pivotally.

A shoulder 2 is formed upon the upright portion 3 of the bracket arm and abutting this shoulder is a disc member 4 which is rotatable on the upright. This disc is provided with a reduced top extension 5 and rotatably mounted upon this extension is the disc holding arm 6.

Discs 4 are placed upon the upright 3 one 45 above the other each with the bottom face abutting the top face of the reduced extension of the one next below so that each successive disc forms with the under disc a lateral support for the arms to hold them in a 50 horizontal position.

The arms are spaced apart according to the depth of the disc members 4 and they are free to rotate on the extension independent the one of the other. Each of the discs 55 is provided with a vertical hole 7 extending through the extension 5 and a pin 8 is in-

serted to extend through the entire arrangement of discs locking them from rotation in relation the one to the other. The upper end of the upright 3 is formed with a flattened 60 side 9 and the central hole of the top disc is shaped to fit the flattened side so that it will be non-rotative on the upright, thus the whole column of discs will be held stationary.

65 A nut 10 is threaded upon the upper end of the upright holding the washer 11 against the top arm.

The arms 6 are formed of wood or metal as may be desired and are provided with the 70 tubular pins 12 arranged centrally of the width adjacent to the outer ends. These pins project upwardly from each arm and form the centre pin for the record disc.

A suitable covering 13 of plush or other 75 material is arranged on the top side of each arm to protect the disc and upon the underside of each arm is arranged a pad 14 of plush or other suitable material which is adapted to engage the surface of the disc 80 resting upon the arm immediately underneath. This pad forms a brushing pad to remove any dust from the record surface before it is used, it being merely necessary to rotate the disc before it is removed from the 85 holder.

The tubular pins 12 provide a means for locking the arms so that the discs cannot be removed. The arms may be secured together 90 in groups by inserting a pin 15 to extend down through the said tubular pins when they are arranged one above the other.

A holder such as described provides very desirable means for storing phonograph records in a manner to ensure their care and enables the discs being removed individually very readily without interference with the records not desired, as any one arm may be swung outwardly on its pivot to allow the record to be removed. The structure is extremely simple and can be produced at very 100 low cost.

What I claim as my invention is:—

1. In a phonograph record holder, an upright arm, a plurality of discs mounted on 105 said upright, each of said discs having a reduced circular axial extension, record holding arms rotatably mounted on the reduced portions of said discs, and means for locking said discs together.

110 2. In a phonograph record holder, an upright arm, a plurality of discs mounted on

said upright, each of said discs having a reduced circular axial extension, record holding arms rotatably mounted on the reduced portions of said discs, said discs also having 5 a vertical orifice extending from top to bottom through the reduced portion, and a pin inserted through said orifices and locking said discs.

3. In a phonograph record holder, an upright arm, a plurality of flat arms rotatably mounted on said upright and spaced apart, each having a tubular pin extending upwardly therefrom adjacent to the outer end, and a locking pin adapted to be inserted through said tubular pins.

PHILIP MORGAN.
